UNITED STATES PATENT OFFICE.

WARREN FRASIER, OF PHILADELPHIA, PENNSYLVANIA, ASSIGNOR TO UNITED SHOE MACHINERY COMPANY, OF PATERSON, NEW JERSEY, A CORPORATION OF NEW JERSEY.

SOLE-LEVELING MACHINE.

1,171,780.

Specification of Letters Patent. Patented Feb. 15, 1916.

Application filed November 17, 1911. Serial No. 660,842.

To all whom it may concern:

Be it known that I, WARREN FRASIER, a citizen of the United States, residing at Philadelphia, in the county of Philadelphia and 5 State of Pennsylvania, have invented certain new and useful Improvements in Sole-Leveling Machines; and I do hereby declare the following to be a full, clear, and exact description of the invention, such as will enable others skilled in the art to which it app- 10 pertains to make and use the same.

The present invention relates to sole leveling machines, and more particularly to that 15 class of leveling machines which comprise a leveling roll and a shoe supporting jack relatively movable to change the relative longitudinal position of the leveling roll and jack.

When leveling the soles of turn shoes, the leveling roll is rotated to impart a rubbing 20 action to the surface of the sole in addition to the leveling pressure which is exerted by the roll. As the leveling roll is rotated continuously in one direction at a higher speed than the travel of the jack, the rubbing action 25 always takes place in the same direction irrespective of the direction of movement of the jack, and when operating upon the lighter grades of shoes, this rubbing movement often displaces the sole sufficiently to 30 distort the shoe and render it unsalable.

One object of the present invention is to 35 equalize the draw upon the sole and enable all grades of shoes to be properly leveled without displacing the sole from its proper position relative to the upper or otherwise distorting the shoe.

With this object in view, one feature of 40 the invention contemplates the provision of a shoe supporting jack, a coöperating leveling roll, means for varying the relative longitudinal position of the roll and jack, and mechanism operatively connected with the roll and acting automatically to cause the roll to rub different portions of the sole in 45 opposite directions while maintaining a constant direction of movement of the jack. Broadly considered, this feature of the invention is not limited to the employment of a continuously rotated roll, but contemplates 50 the provision of a roll with any mechanism operatively connected thereto for causing the roll to rub the sole of a shoe.

Machines of this character are also em- 55 ployed for leveling very light shoes worn by

infants and children and commonly known as "cacks", in which it is desired to level the entire surface of the sole, including the heel portion or heel seat. When employing existing machines of this type for this purpose, the edge of the sole at the heel seat is 60 pulled away from the upper and counter when the leveling roll rides onto the shoe at this point. In order to avoid this, the machines are often arranged to stop the travel of the jack before the roll has reached the rear edge of 65 the heel seat. This mode of operation, however, is obviously objectionable, as a ridge is formed upon the margin of the sole which is not leveled and stands up from the remaining surface of the sole. 70

A further object of the invention is to enable the entire surface of the sole, including the heel seat, to be properly leveled without marring the edges of the sole at either the heel or toe, or straining the fastenings between the sole and upper of the shoe at these points. 75

With this object in view, a further feature of the invention consists in the combination, with a shoe supporting jack and leveling roll, of mechanism for rotating the roll in the direction of travel of the jack as the roll is moved into engagement with the shoe at the toe and heel respectively. 80

Still further features of the invention 85 comprise certain novel features of construction, combinations and arrangements of parts hereinafter described and claimed, the advantages of which will be apparent to those skilled in the art from the following 90 description.

The several features of the invention will be clearly understood from an inspection of the accompanying drawings, in which—

Figure 1 represents a side elevation of a 95 leveling machine embodying the several features of the invention in their preferred form; Fig. 2 is a view in side elevation looking at the opposite side of the leveling machine from Fig. 1; Fig. 3 is a top plan view 100 of the leveling machine; Fig. 4 is a detail showing a side elevation of a portion of the operating mechanism for the leveling roll; Fig. 5 is a detail showing an end elevation 105 of a portion of the mechanism for operating the roll; Fig. 6 is a detail view illustrating the mechanism shown in Fig. 5, looking at the same from one side; Figs. 7 and 8 are de-

tails of the operating mechanism; Fig. 9 is a section upon the line 9-9 of Fig. 3; and Fig. 10 is a view, partly diagrammatic, illustrating the action of the leveling roll 5 upon the sole of a shoe.

Certain parts of the machine are similar in their construction and mode of operation to the machine shown and described in the patent to Andrew Eppler, No. 1,004,155, dated September 26, 1911, and will be only briefly described herein in consequence thereof.

The sole leveling roll is indicated at 1 and is journaled in the forward end of a frame 2 which is pivotally mounted at its rear end in the upper rear portion of the machine frame 3. The shoe is supported upon a suitable jack 4 which is pivotally mounted at 5 on the jack carrying frame 6. The shoe supporting jack 4 is rocked laterally by the operator to vary the relative lateral inclination of the leveling roll and jack and at the same time is moved back and forth beneath the leveling roll to effect a relative longitudinal movement of the leveling roll and jack. To this end the jack carrying frame 6 is pivotally mounted in the machine frame at 7, and is oscillated by a connecting rod 8 and crank 9. The crank 9 is mounted upon a crank shaft 10 to which a partial rotation is imparted periodically in opposite directions by a large friction disk 11 engaged alternately by a pair of small friction disks locked to the pulleys 12 and 13 respectively. A rocker frame 14 is pivotally connected to the machine frame at 15 and is operated to throw either of the small friction disks into engagement with the friction disk 11 by a handle 16 conveniently accessible to the operator. A continuous rotation is imparted to the pulleys 12 and 13 from a drive pulley 17 through a belt connection 18. To prevent an overthrow of the jack supporting frame in case the operator does not move the handle 16 at the proper time, an automatic stop mechanism is provided which is indicated at 19. The roll 1 is yieldingly held against the sole of the shoe by a treadle 22 which is connected to the roll supporting frame 2 through a spring 23. The dead weight of the leveling roll and operating mechanism is supported by a spring 24 connecting the rear end of the supporting frame 2 with the machine frame 3. The leveling roll is continuously rotated during the operation of the machine by a drive pulley 25 supported in the upper rear portion of the machine frame and operated from the main drive pulley 26 through a suitable belt connection 27.

These machines are employed principally for leveling the soles of turn shoes and in addition to the downward pressure which serves to bed the sole upon the last, a rubbing action is exerted upon the surface of

the sole which smooths out the surface and imparts the desired finish to the same. When this rubbing action is always directed toward the same end of the shoe, it tends to distort the lighter grades of shoes unduly and in addition the margin of the sole at the opposite end of the shoe is rubbed up when the roll rides upon the shoe at this point. In the present invention the direction of rotation of the roll is reversed without changing the direction of movement of the jack, and this reversal of the roll takes place approximately at the ball line of the shoe, thus rubbing the shank and ball portions of the sole in opposite directions. In addition, the driving mechanism of the roll is so arranged that when the roll rides on the toe and heel of the shoe respectively, the direction of rotation of the roll in each instance corresponds with the direction of movement of the jack. In the simplest and most efficient form of the invention which has as yet been devised, this is accomplished by providing two driving members for the leveling roll which are continuously rotated in opposite directions, and automatic means for operatively connecting the roll with either of the driving members during the continuous movement of the jack in one direction. To this end the drive pulley 25 is mounted upon a transverse shaft 30 upon the opposite ends of which are keyed a pair of pulleys 31 and 32. Upon the front end of the supporting frame 2 and adjacent to the leveling roll 1, a pair of pulleys 33 and 34 are journaled in alinement respectively with the pulleys 31 and 32. The pulleys 33 and 34 are connected to the drive pulleys 31 and 32 by a cross belt 35 and open belt 36 respectively, thus imparting a continuous rotation in opposite directions to the pulleys 33 and 34. In order to operatively connect either of these pulleys with the leveling roll 1 as desired, a pair of multiple disk clutches 38 are provided. As the operative connections between the pulleys 33 and 34 and the clutches 38 are identical in their construction and mode of operation, it is only considered necessary for a clear understanding of the machine to describe one of the connections. One member 39 of the clutch 38 is keyed to the inner end of a shaft 40 upon the outer end of which the pulley 34 is fastened. The second member 41 of the clutch is formed integrally with a sleeve 42 which is journaled in the frame 2 and which forms a bearing for the shaft 40. A plurality of metallic disks 43 are held between the clutch members and upon a relative movement of the members 125 to restrict the space between them, the disks 43 are pressed together, thus serving to lock the two members together and drive the sleeve 42. The sleeve 42 is connected to the leveling roll 1 by a pair of intermeshing 130

gears 44 and 45 which are keyed to the sleeve 42 and roll supporting shaft 46 respectively.

In order to automatically control the direction of rotation of the leveling roll, means are provided for simultaneously engaging and disengaging the two clutches at predetermined intervals during the continuous operation of the machine. A path cam 50 is mounted upon the crank shaft 10 and is capable of circumferential adjustment relative thereto by a plurality of bolt and slot connections 51. By adjusting the cam 50 in a circumferential direction, the reversal 15 of the roll may be made to take place at any desired point in the travel of the jack. The cam 50 is operatively connected to one end of a lever 52 which is pivoted at 53 to the frame of the machine and which is connected at its opposite end to an actuating rod 55. In order to form a yielding connection between the lever 52 and rod 55 a 20 pair of springs 56 and 57 are interposed between opposite faces of the lever and a pair of lock nuts 58 and 59 respectively. The actuating rod 55 is connected to a rock shaft 60 by a crank arm 61 so that upon an oscillation of the lever 52 about its pivotal point 53 the rock shaft 60 is oscillated in its 25 bearings by the crank arm 61. A second and longer arm 62 is keyed to the rock shaft 60 and this second arm 62 is operatively connected to a crank arm 64 through a link 65. To enable the movement of the crank arm 30 64 to be varied it is provided with a slot 63 in which one end of the link 65 is adjustably fastened, and by moving the end of the link toward or from the axis of the crank, the oscillation of the crank may be decreased or increased as desired. The crank arm 64 is 35 provided with an internally threaded hub 66 which meshes with a coarse screw thread 67 formed upon a shaft 68. The shaft 68 is supported in a bracket 69 fastened to the 40 machine frame and provided with a pair of downwardly projecting ears 70 in which the shaft 68 is journaled. In order to move the shaft 68 longitudinally upon an oscillation of the arm 64, a finger 70^a projects from the 45 shaft 68 and engages with a stationary pin 71, thus preventing a rotation of the shaft in its bearings. The outer end of the finger 70^a is provided with a recess in which the pin is seated, as shown clearly in Fig. 8, in 50 order to prevent any lateral movement of the finger relatively to the pin but to allow a longitudinal sliding movement of the finger upon the pin. The pin 71 is detachably fastened in a bracket 72 in which the shaft 55 60 is journaled, and in order to accurately position the shaft 60 and pin 71 with relation to their coöperating parts, the bracket 72 is detachably fastened to the machine frame and is universally adjustable thereon. 65 This is accomplished by providing a pair of

transverse screws 73 which are threaded in the bracket and which bear upon opposite sides of a cross member 74 and a clamp plate 75 which engages underneath the cross member 74 and is detachably connected to the 70 bracket 72 by a plurality of adjusting screws 76. A rock shaft 77 extends longitudinally of the supporting frame 2 and is journaled at its opposite ends in the frame 2 and the bracket 69. A short shaft 78 is journaled in the bracket 69 parallel to the shaft 77 and is operatively connected to the latter by a pair of toothed segments 79 and 80. The shaft 78 is oscillated in its bearings upon a longitudinal movement of the shaft 68 by a depending arm 81 which is locked against rotation relatively to the shaft 78 and is provided with a bifurcated portion 82 engaging a grooved collar 83 fastened to the shaft 68. In order to adjust the arm 81 relatively to 85 the shaft 78, an upstanding web 85 is keyed to the shaft and is engaged upon opposite sides by a pair of adjusting screws 86 which are threadedly mounted in ears 87 formed upon the arm 81. 90

From an inspection of Fig. 9, it will be noted that each of the clutch members 39 is connected to an operating arm 88 pivotally mounted upon the roll supporting frame at 90. The upper ends of the operating arms are connected by a link indicated at 91 which is adjustable in length to vary the relative angular position of the arms and adjust them to properly actuate the clutches 38. This adjustment is effected by 95 forming the link of two members 92 and 93 which are connected together at their inner ends by a left and right screw-threaded member 94. The rock shaft 79 forms one of the pivotal connections 90 and thus upon an 100 oscillation of the shaft 77 the arms 88 are rocked simultaneously in the same direction to engage one clutch and disengage the 105 opposite clutch. 110

The operation of the machine is as follows: Assuming that the shoe to be leveled has been properly jacked and that the various parts of the machine have been adjusted to properly operate upon the particular shoe, the operating lever 16 is then manipulated to move the jack and shoe beneath the leveling roll. When the machine is first started, it will be assumed that the leveling roll is actuated from the drive pulley 25 through the crossed belt 35, thus rotating 115 the roll in the direction of movement of the shoe and enabling the roll to ride onto the toe of the shoe properly without straining the fastenings or injuring the edge of the sole. As the crank shaft 10 is rotated 120 the roll is caused to traverse longitudinally of the sole and when the roll has reached a point upon the sole substantially coincident with the ball line, the path cam 50 is arranged to actuate the control mechanism 125 130

to disconnect the crossed belt drive from the leveling roll and connect the open belt drive thereto. The direction of rotation of the leveling roll is now reversed, and the 5 leveling roll, as shown in Fig. 10, is rotated in a direction opposite to the direction of movement of the jack. The leveling roll traverses the entire length of the heel seat and the roll rides off the shoe before the 10 direction of movement of the jack is reversed. Upon reversing the direction of movement of the jack, the roll and jack have the same direction of movement and the roll is enabled to ride onto the heel end of the shoe 15 without injury to the same. The roll continues to rotate in this direction until approximately the same point is reached at which it was previously reversed, when the automatic control is again actuated and the 20 direction of rotation of the roll is now reversed and is opposite to the direction of movement of the jack. With this mode of operation, the sole is rubbed in opposite directions over the ball and shank portions 25 and the entire sole is leveled without injury to the projecting margin of the sole at the heel and toe.

While it is preferred to employ the specific construction and arrangement of 30 parts shown and described, it will be understood that this construction and arrangement is not essential except so far as specified in the claims, and may be changed or modified without departing from the 35 broader features of the invention.

What is claimed is:—

1. A sole leveling machine, having, in combination, a shoe supporting jack, a leveling roll, means for changing the relative 40 longitudinal position of the roll and jack to cause the roll to traverse over the sole and pass off of opposite ends of the shoe, and means for actuating the roll in the direction of travel of the jack as the roll is moved 45 into engagement with each end of the shoe, substantially as described.

2. A sole leveling machine having, in combination, a shoe supporting jack, a leveling roll, means for varying the relative longitudinal position of the roll and jack, and mechanism operatively connected with the roll and acting automatically to cause the roll to rub each portion of the sole in one direction only and different portions of the 55 sole in opposite directions while maintaining a constant direction of movement of the jack, substantially as described.

3. A sole leveling machine, having, in combination, a shoe supporting jack, a leveling roll, means for varying the relative longitudinal position of the roll and jack, and mechanism operatively connected with the roll and acting automatically to cause the roll to rub the sole in opposite directions 60 65 from the ball line outwardly toward the

ends of the shoe during the relative movement of the roll and jack in one direction, substantially as described.

4. A sole leveling machine, having, in combination, a shoe supporting jack, a leveling roll, means for varying the relative longitudinal position of the roll and jack, a pair of driving members rotated in opposite directions, and means for automatically connecting alternate driving members to 70 the roll as the jack is moved thereunder to rotate the roll in opposite directions, substantially as described.

5. A sole leveling machine, having, in combination, a shoe supporting jack, a leveling roll, means for varying the relative longitudinal position of the roll and jack, a pair of driving members rotated in opposite directions, a cam, and operative connections between the cam and driving members to automatically connect one of the driving members to the roll, substantially as described. 85

6. A sole leveling machine, comprising a leveling roll, a pair of driving members rotated in opposite directions, a rotary cam having provision for circumferential adjustment, and operative connections between the cam and driving members to enable the driving members to be automatically connected to the leveling roll, substantially as described. 90

7. A sole leveling machine, having, in combination, a shoe supporting jack, a leveling roll, means for varying the relative longitudinal position of the roll and jack, a pair of driving members, a rock shaft arranged to connect either of the driving members to the leveling roll, a depending arm, a shaft connected to the arm, and means for moving the last mentioned shaft 105 longitudinally, substantially as described.

8. A sole leveling machine, having, in combination, a shoe supporting jack, a leveling roll, means for varying the relative longitudinal position of the roll and jack, a pair of driving members, a rock shaft, a depending arm, means for varying the angular relation of the arm and rock shaft, a shaft connected to the arm, and means for moving the last mentioned shaft 110 longitudinally, substantially as described. 115

9. A sole leveling machine, comprising a leveling roll, a pair of driving members, a rock shaft arranged to connect either of the driving members to the leveling roll, a sliding shaft, a crank arm, means for oscillating the crank arm, and connections between the arm and last mentioned shaft for moving the shaft longitudinally as the arm is 120 oscillated to connect one of the driving members to the leveling roll, substantially as described.

10. A sole leveling machine, having, in combination, a leveling device, a shoe sup- 125 130

porting jack, means for varying the relative longitudinal position of the leveling device and jack, and mechanism operatively connected with the leveling device and acting automatically to cause the leveling device to exert a lengthwise rubbing action upon each portion of the sole in one direction only and different portions of the sole in opposite directions, substantially as described.

11. A sole leveling machine, having, in combination, a shoe supporting jack, a leveling device, means for changing the relative longitudinal position of the leveling device and jack to cause the leveling device to traverse over the shoe sole and on to and off of the opposite ends of the shoe, and means for actuating the leveling device to always rub the margin of the sole outwardly in the direction of the length of the shoe when moving into engagement with the ends of the shoe, substantially as described.

12. A sole leveling machine, having, in combination, a shoe supporting jack, a level-

ing roll, means for moving the jack back and forth beneath the roll to cause the roll to traverse over the ball portion of the shoe sole, and means for actuating the roll to rub the sole in the direction of the toe irrespective of the direction of movement of the jack, substantially as described.

13. A sole leveling machine, having, in combination, a shoe supporting jack, a leveling roll, means for changing the relative longitudinal position of the roll and jack to cause the leveling roll to traverse over the shank and ball portion of a shoe sole, and means for actuating the roll to rub each portion of the sole in one direction only, one portion of the sole being rubbed toward the heel, and another portion of the sole being rubbed toward the toe respectively, substantially as described.
